POWER SUPPLY CABLE HATCH FOR A HOUSE TRAILER OR SIMILAR ARTICLE

Joseph A. Hill, Glen Ellyn, Ill., assignor to Hub Industries, Inc., Chicago, Ill., a corporation of Illinois

Filed Dec. 15, 1959, Ser. No. 58,672

Term of patent 14 years

(Cl. D26—5)

Fig. 6.

Fig. 7

Figure 1 is a front perspective view of a power supply cable hatch for a house trailer or similar article embodying my new design, with the door thereof in closed position;

Figure 2 is a front view of a power supply cable hatch for a house trailer or similar article embodying my new design, with the door thereof in closed position;

Figure 3 is a side elevation of a power supply cable hatch for a house trailer or similar article of Figure 1 with the door thereof in closed position;

Figure 4 is a side elevation of a power supply cable hatch for a house trailer or similar article of Figure 1 with the door thereof in open position;

Figure 5 is a bottom plan view of a power supply cable hatch for a house trailer or similar article of Figure 1 with the door thereof in closed position;

Figure 6 is a vertical sectional view of a power supply cable hatch for a house trailer or similar article taken on line 6-6 of Figure 2; and

Figure 7 is a horizontal sectional view taken on line 7-7 of Figure 2.

I claim:

The ornamental design for a power supply cable hatch for a house trailer or similar article, substantially as shown and described.
